(57) **CLAIM**

The ornamental design for a metal beverage container, as shown and described.

DESCRIPTION

FIG. 1 is a front perspective view of the metal beverage container;

FIG. 2 is a top plan view thereof;

FIG. 3 is front elevation view thereof;

FIG. 4 is a bottom plan view thereof;

FIG. 5 is a front perspective view of a metal beverage container according to an alternative embodiment;

FIG. 6 is a top plan view of the embodiment of FIG. 5;

FIG. 7 is a front elevation view of the embodiment of FIG. 5; and,

FIG. 8 is a bottom plan view of the embodiment of FIG. 5. The broken lines are provided for illustrating environment and form no part of the claimed design.

1 Claim, 6 Drawing Sheets
